ATTORNEY

UNITED STATES PATENT OFFICE.

EMIL WOHLERS, OF NEW YORK, N. Y.

INJECTOR.

SPECIFICATION forming part of Letters Patent No. 276,319, dated April 24, 1883.

Application filed February 5, 1883. (Model.)

To all whom it may concern:

Be it known that I, EMIL WOHLERS, of the city, county, and State of New York, have invented certain new and useful Improvements 5 in Injectors, of which the following is a specification.

This invention has reference to that class of injectors in which a supplementary jet or 10 injector is used for lifting the water through the injector preparatory to starting the same; and the invention consists of an injector in which the steam-chamber and its valve and the valved steam conduit or channel leading to the injector are arranged at one side of the body 15 of the injector and the water-supply pipe and its valve at the opposite side of the same, the steam-chamber, steam-channel for the injector, and the water-supply chamber being cast integral with the body of the injector. The 20 steam-chamber is separated from the aspiration-chamber in the body of the injector by an intermediate chamber, so as to prevent the formation of steam in the aspiration-chamber and the destruction of the vacuum. The steam- 25 chamber of the injector extends around the body of the injector and terminates in a nozzle in the overflow-tube of the overflow-chamber, the overflow-channel of which extends around the other side of the injector-body.

30 In the accompanying drawings, Figure 1 represents a vertical longitudinal section of my improved injector, and Figs. 2 and 3 are vertical transverse sections of the same on lines *xx* and *yy*, Fig. 1.

35 Similar letters of reference indicate corresponding parts.

Referring to the drawings, A represents the injector-body or main casting, at the interior of which are arranged the steam-nozzle *a*, the 40 combining-cones *b* *b'*, and the discharge-tube *d*, all of which are arranged in line with the axis of the injector-body A and through the delivery end of the same, they being secured by means of suitable taps in properly relative 45 position to each other.

The steam-supply conduit or chamber B is arranged at one side of the injector-body or main casting A and the water-supply tube C at the other side of the same. The steam- 50 chamber B is provided with a valve, *B'*, and

the water-supply tube C with a water-regulating valve, *C'*.

Between the steam-chamber B and the aspiration-chamber *a'* of the injector is arranged an intermediate semi-annular chamber, *B*², 55 which is inclosed by the end wall of the body A, the wall of the aspiration-chamber, and a side wall of the steam-chamber, as shown clearly in Fig. 1. This intermediate steam-chamber, *B*², extends from the valve *B'* of the steam-chamber B to the steam-nozzle *a*, and prevents thereby the direct contact of steam with the wall of the aspiration-chamber *a'*. The latter is thereby not heated up by the action of the steam, and consequently the 65 vacuum in the injector-body not injured or destroyed by the generation of steam. The intermediate chamber, *B*², is provided with a detachable screw-cap, *a*², in line with the longitudinal axis of the injector-body, so that when 70 the cap is removed the steam-nozzle, cones, and delivery-tube can be readily cleaned by the introduction of a suitable cleaning device whenever, for some reason or other, the injector should not do its work properly.

An auxiliary valve, D, is arranged, preferably in line with the steam-valve *B'*, at the opposite side of the steam-chamber B. The auxiliary valve D closes a steam-channel, *D'*, that runs first along the injector-body A, and then 80 around the same, at one side thereof, to a nozzle, *f*, which is arranged at the interior of the overflow-tube F of the overflow-chamber G. The overflow-tube F communicates with the open air, and is connected with the overflow-chamber G at the interior of the injector-body by a valved channel, *f'*, that extends around the injector-body at the side opposite to the steam-channel *D'*, as shown clearly in Fig. 3. The injector-channel *D'* and the channel *f'* that 85 connects the overflow-chamber G with the overflow-tube F, also the steam-chamber B and the water-supply tube C, are all cast integral with the injector-body A, forming one casting, as shown clearly by full black lines in 90 Fig. 1.

The operation of the injector is the same as in other injectors which are provided with supplementary jets or ejectors. The auxiliary valve D is first opened, so that the steam can 95

pass through the ejector-channel D' , nozzle f , and the overflow-tube F to the outside. The steam creates thereby a vacuum in the overflow-chamber G , and causes thereby the water 5 to be lifted through the water-supply tube C , and to be drawn through the combining-cones, overflow-chamber, and overflow-channel to the overflow-tube F . As soon as water escapes 10 through the overflow-tube F the steam-valve B' is opened and the injector begins its regular work by admitting the steam through the intermediate chamber, B^2 , and steam-nozzle a , so as to act upon the water and force it through 15 the combining-cones and delivery-tube in the usual well-known manner. As the steam cannot exert any injurious influence upon the vacuum in the aspiration-chamber, the injector works instantly and with full force on the opening of the steam-valve, and performs its 20 function in a very reliable and effective manner.

Having thus described my invention, I claim as new and desire to secure by Letters Patent—

1. In an injector, the combination of the injector-body having a valved steam-chamber at 25 one side and a valved water-supply tube at the other side thereof, with an intermediate chamber located between the wall of the steam-chamber and the wall of the aspiration-chamber of the injector, so that the direct heating 30 of the wall of the aspiration-chamber by the steam is prevented, substantially as set forth.

2. In an injector, the combination of the injector-body A , having a valved steam-chamber, B , at one side and a valved water-supply tube, C , at the other side thereof, with an intermediate chamber, B^2 , located between the steam-chamber and the aspiration-chamber, said intermediate chamber having a removable screw- 35

cap in line with the steam-nozzle, combining-cones, and delivery-tube of the injector, substantially as described. 40

3. In an injector, the combination, with the injector-body A , having a valved steam-chamber, B , at one side and a valved water-supply tube, C , at the other side thereof, of an ejector-valve, D , and an ejector-channel, D' , leading from the steam-chamber, along the injector-body and at one side thereof, to the ejector-nozzle in the overflow-tube of the overflow-chamber, substantially as and for the purpose set forth. 45

4. In an injector, the combination of the injector-body A , having a steam-chamber, B , and steam-valve B' at one side thereof and a water-supply tube, C , and water-regulating valve C' at the other side thereof, an ejector-valve, D , in line with the steam-valve B' , an ejector-channel, D' , leading from the steam-chamber, along one side of the injector-body, to the ejector-nozzle f , and a valved overflow-channel, f' , that extends around the other side of the injector-body and connects the overflow-chamber G with the overflow-tube F , substantially as and for the purpose set forth. 55

5. An injector in which the steam-chamber B , intermediate chamber, B^2 , ejector-channel D' , water-supply tube, and the longitudinal body are made in one integral casting, substantially as set forth. 60

In testimony that I claim the foregoing as my invention I have signed my name in presence of two subscribing witnesses.

EMIL WOHLERS.
